UNITED STATES PATENT OFFICE.

ROSWELL A. MOORE, OF BERLIN, CONNECTICUT, ASSIGNOR TO WATERBURY BUCKLE COMPANY, A CORPORATION OF CONNECTICUT.

DESIGN FOR A GARMENT-SUPPORTER.

No. 40,199.

Specification for Design.

Patented Aug. 3, 1909.

Application filed February 2, 1909. Serial No. 475,717. Term of patent 14 years.

To all whom it may concern:

Be it known that I, ROSWELL A. MOORE, a citizen of the United States, residing at Berlin, in the county of Hartford and State of Connecticut, have invented a new, original, and ornamental Design for Garment-Supporters, of which the following is a specification, reference being had to the accompanying drawing, forming part thereof.

Figure 1 is a front elevation of a garment supporter, showing my new design. Fig. 2 is a side elevation of same.

I claim:

The ornamental design for a garment supporter, as shown.

ROSWELL A. MOORE.
